UNITED STATES PATENT OFFICE.

HERBERT A. DAUM, OF INDIANAPOLIS, INDIANA.

REVERSING GEARING FOR DISHWASHING MACHINES.

Application filed January 9, 1922. Serial No. 528,060.

This invention relates to washing machines of that class adapted primarily for washing dishes, and the like, although the same may be successfully used for washing 5 clothing and other fabrics. One feature of the invention is the provision of an article receiving cage mounted for reciprocal rotating movement.

A further feature of the invention is the 10 provision of yielding means between the driving and driven elements whereby the rotating element will be gradually stopped and the movement thereof reversed, while the driven element will be instantly re- 15versed.

A further feature of the invention is the 20 provision of means for automatically reversing the rotation of parts of the device while the source of power continues to rotate in the same direction.

A further feature of the invention is the 25 provision of means for frictionally engaging the article holding cage with the driving element therefor.

And a further feature of the invention is 30 in so constructing the automatically operated reversing mechanism that the article containing cage may rotate more than one revolution before the revolution thereof is reversed.

Other objects and advantages will be hereinafter more fully set forth and pointed out in the accompanying specification.

In the accompanying drawings, which are 35 made a part of this application,

Figure 1 is a side elevation partly in section of the washing device,

Figure 2 is a sectional view as seen on line 2-2, Figure 1,

Figure 3 is a sectional view as seen on line 3-3, Figure 2,

Figure 4 is a sectional view as seen on line 4-4, Figure 3;

Figure 5 is a sectional view as seen on line 5-5, Figure 3, showing the yielding connection between the driving and driven element in normal position,

Figure 6 is a similar view showing the parts of the device at the instant of reversing the rotation of the driven element,

Figure 7 is an elevation of the automatic reversing mechanism and parts associated therewith with the housing for said parts in section,

Figure 8 is an enlarged detail plan view 55 of a part of the tripping mechanism, and Figure 9 is a sectional view thereof.

Referring to the drawings in which similar reference numerals designate corresponding parts throughout the several views, 1 60 indicates a frame or support upon which is mounted a receptacle 2, said receptacle being arranged to contain water, and mounted within said receptacle is a cage 3, the walls of which are formed of segmental sections 65 of cross bars 4, said bars, when in assembled relation, engaging with bottom and top members 5 and 6, and these parts are all secured together, preferably by bolts 7.

The receptacle 2 is mounted upon the bed 70 plate 8 of the frame 1, the top edge of the receptacle having a band 9 fitting thereover, in the under face of which is a notch 10 for the reception of the upper edge of the receptacle 2. The lower edge of the receptacle 75 is seated in a notch 11 in the bed plate 8, bolts 12 being employed for clamping the receptacle and band to the bed plate.

At the center of the bottom member 5 is 80 provided a conical seat 13 with which frictionally engages a cone 14 at the upper end of a vertically extending driven shaft 15, said shaft extending through a stuffing box 16 in the bed plate 8, the lower end of the shaft 15 being fixed to a housing 18. The 85 housing 18 is provided with transversely extending barrels 19 in which are positioned compression springs 20, the opposite ends of each spring having heads 21 and 22, the heads 21 engaging with adjusting screws 90 23, while the heads 22 engage with a cam 24 mounted upon the upper end of a driving shaft 25. The cam is elliptical so that when turned to one position the springs will be compressed, and when turned to another 95 position, with respect to the springs, will form a substantially stationary driving connection between the shafts 15 and 25. The lower end of the shaft 25 enters a casing 26, and in said casing is a gear 27 employed for driving the shaft 25, and intermeshing with the gear 27 is a pair of pinions 28 and 29, which are in turn rotatably mounted upon vertically extending shafts 30 and 31, respectively. Slidably mounted upon the 100 shafts 30 and 31 are clutch members 32 and 33, respectively, the upper ends of which are provided with clutch faces 34 and 35, re-

105

spectively, for engagement with the hubs of the pinions 28 and 29, the clutch members 32 and 33 being associated with a rocking beam 36 which is pivotally connected at its longitudinal center, preferably to the wall of the casing 26. The rocking beam 36 is so connected with the clutch members that when one of the clutches is engaged with its respective pinion, the other clutch 10 will be out of engagement with its respective pinion, and as the clutch members and the pinions are rotatably mounted on the shafts 30 and 31, one of the pinions will run idle while the other pinion is being 15 driven, and as the pinions run in opposition to each other the change in drive from one pinion to the other will serve to reverse the rotation of the gear 27, and the cage 3 associated therewith. The shafts 30 and 31 20 have worm gears 37 and 38, rotatably mounted thereon, with which co-operates a worm 39 mounted upon a shaft 40, said latter shaft and worm being driven from any suitable source, and to permit vertical movement of the clutch members 32 and 33, and at the same time positively drive the same 25 from the worm gears, a sleeve 41 is attached to each of the worm gears, said sleeves having grooves 42 for engagement with keys 43 on the clutch members 32 and 33, consequently the clutch members may readily move upwardly or downwardly on their respective shafts, and at the same time be 30 positively rotated with the worm gears.

35 The clutch members 32 and 33 are automatically operated for engaging one or the other with the pinions 28 and 29 by providing a trip arm 44 on the rocking beam 36, the upper end of which enters a slot 45 in a tripping plate 46, the plate being pivotally mounted on the shaft 25 so that it 40 may be swung in the arc of a circle for engaging the ends of the slot 45 with the trip arm 44. In order to prevent the tripping plate 46 resting at a neutral point in its arc of movement, a plunger 47 is slidably mounted through a pivot 48 in one wall of the casing 26, the opposite end of the plunger having a ball 49 which co-operates 45 with a socket 50 on one face of an extension 51 located on the plate 46, substantially at the longitudinal center of the slot 45, and by placing a compression spring 52 around the plunger 47 the tension of said spring 55 will serve to complete the full stroke of the tripping plate 46 in either direction. The tripping plate 46 is moved laterally in opposite directions by placing on the extension 51 an upwardly projecting stud 53 which 60 co-operates with an angular-shaped trigger 54 pivoted to the under face of the gear 27, the swinging movement of the trigger 54 being regulated by a stop 55 also carried by the gear 27, and it will be readily seen 65 that when one arm of the trigger is against

the stop, as soon as the gear 27 has made a complete revolution, the arm of the trigger so resting against the stop will strike the stud 53 and impart lateral swinging movement to the tripping plate 46, said movement being continued until the tripping plate has been moved past its center of gravity, whereupon the tension of the spring 52 will complete the swinging movement of the plate and as the trip arm 44 contacts with the end of the slot 45 the rocking beam 36 will be operated to release one of the clutch members and engage the other clutch member, thereby reversing the rotation of the gear 27 and cage 3.

It is preferable to permit the gear 27, and the dish containing tray associated therewith, to make two complete revolutions before the rotation thereof is reversed, and this is accomplished by employing the angular-shaped trigger for operating the reversing mechanism, as it will be seen that after the rotation of the gear 27 has been reversed the arm of the trigger previously employed for operating the tripping mechanism will, upon the next reverse rotation of the gear 27, swing away from the stop 55 and move the other arm of the trigger to such point that at the next revolution of the gear 27 the latter arm of the trigger will be moved against the stop, thereby causing the tripping plate to swing in the opposite direction.

In operation, after the dishes, or other articles to be washed, are placed within the cage 3, the water within the receptacle 2, having been heated from the heating tank 56 or other source, the motor 57 is energized which sets up operation of the gear 39 through the shaft 40. The clutch members being set in the position shown in Figure 7 of the drawings, the gear 28 will be rotated and the gear 27, together with the cage 3, rotated to the left. At the first complete revolution of the gear 27, the finger of the trigger 54 engaging the stop 55 will be moved away from the stop and the other finger of the trigger 54 moved to such position that it will engage the stud 53 on the next revolution of the gear 27, the continued rotation of the gear 27 moving the tripping plate 46 past its center of gravity, when the tension of the spring 52 will complete the movement of the tripping plate 46 and engage the clutch member 33 with the pinion 29, and as the pinion 29 is rotating in a direction reverse to the pinion 28, the rotation of the gear 27 will be likewise reversed.

To prevent the momentum of the revolving cage 3 being forcibly directed against the shafts and parts driving the same, the elliptical cam 24 is provided, which is controlled by the compression springs 20, the cage 3 having a partial additional rotation

over the gear 27, owing to the fact that the springs 20 yield when the force of the cage is directed thereagainst. As soon, however, as the momentum of the cage is stopped the pressure of the springs against the cam will start the cage on its reverse rotation and eventually return the cage to its proper cooperative position with the gear 27. By revolving the cage 3 and intermittently reversing the rotation thereof, the water within the receptacle 2 is sufficiently agitated that it will thoroughly remove all particles adhering to the dishes deposited in the cage, and this reversing motion is accomplished 10 without reversing or changing the direction of travel of the motor or the gears directly associated therewith.

While this device is designed primarily for washing dishes it may be used with equal success in washing clothing or articles of fabric, as the agitation of the water through the reversing of the rotating movement of the cage will more thoroughly force the water through the fabrics and cleanse the same.

Having thus fully described my said invention, what I claim as new and desire to secure by Letters Patent, is:

1. In a yielding reversing gearing the combination of a driving shaft, a worm fixed thereon, parallel shafts at an angle to said driving shaft, sleeves loosely mounted on two of said parallel shafts and having gears fixed thereon meshing with the worm on the driving shaft, longitudinally slideable clutch members rotatable with said sleeves, pinions carried on the opposite ends of two of said parallel shafts meshing with a gear fixed on another parallel shaft, said gear and shaft being adapted to be rotated by said pinions alternately in opposite directions, substantially as set forth.

2. In combination a driving shaft having a worm thereon, a plurality of parallel shafts arranged at an angle thereto, one of said parallel shafts being adapted to rotate a device alternately in opposite directions and having a gear fixed thereon, pinions loosely mounted on the adjacent ends of two other parallel shafts in mesh with said fixed gear, said other parallel shafts having sleeves fixed on their opposite ends provided with gears in mesh with a worm on said driving shaft, clutch members on each of said last mentioned parallel shafts between said sleeves and pinions and rotatable with said sleeves, a rocking beam for alternately moving said clutch members into and out of engagement with said pinions, a trip arm on said rocking beam, a tripping plate having a slot therein for engagement with said arm, means associated with said tripping plate for moving the same in the arc of a circle in opposite directions, and a spring projected rod for completing the movement of the tripping plate when shifted from one position to another, substantially as set forth.

3. In combination a driving shaft having a worm thereon, a plurality of parallel shafts arranged at an angle thereto, one of said parallel shafts being adapted to rotate a device alternately in opposite directions and having a gear fixed thereon, pinions loosely

mounted on the adjacent ends of two other parallel shafts in mesh with said fixed gear, said other parallel shafts having sleeves fixed on their opposite ends provided with gears in mesh with a worm on said driven shaft, clutch members on each of said last mentioned parallel shafts between said sleeves and pinions and rotatable with said sleeves, a rocking beam for alternately moving said clutch members into and out of engagement with said pinions, a trip arm on said rocking beam, a tripping plate having a slot therein for engagement with said arm, means associated with said tripping plate for moving the same in the arc of a circle in opposite directions, substantially as set forth.

4. In combination a driving shaft having a worm thereon, a plurality of parallel shafts arranged at an angle thereto, one of said parallel shafts being adapted to rotate a device alternately in opposite directions and having a gear fixed thereon, pinions loosely mounted on the adjacent ends of two other parallel shafts in mesh with said fixed gear, said other parallel shafts having sleeves fixed on their opposite ends provided with gears in mesh with a worm on said driving shaft, clutch members on each of said last mentioned parallel shafts between said sleeves and pinions and rotatable with said sleeves, a rocking beam for alternately moving said clutch members into and out of engagement with said pinions, a trip arm on said rocking beam, a tripping plate having a slot therein for engagement with said arm, means associated with said tripping plate for moving the same in the arc of a circle in opposite directions, substantially as set forth.

5. A reversing gearing comprising a driving shaft having a worm thereon, parallel shafts at an angle to said driving shaft, sleeves loosely mounted on said parallel shafts for engagement with the worm on said driving shaft, clutch members rotatable with said sleeves, means for operating said clutch members, pinions carried by said parallel shafts and a gear and shaft adapted to be rotated by said pinions alternately in opposite directions.

6. A reversing gearing comprising a driving shaft having a worm thereon, a plurality of parallel shafts at an angle thereto a gear on one of said parallel shafts, sleeves loosely mounted on a pair of said parallel shafts and having gears fixed thereon meshing with the worm on the driving shaft, longitudinally slideable clutch members rotatable with said sleeves, pinions carried on the opposite ends of said pair of parallel shafts meshing with said gear fixed on one of said parallel shafts and adapted to be en-

gaged by said clutch members for rotating said pinions alternately in opposite directions, substantially as set forth.

7. A reversing gearing comprising a driving shaft, a plurality of parallel shafts at an angle thereto, one of said parallel shafts being adapted to rotate a device alternately in opposite directions and having a gear fixed thereon, pinions loosely mounted on the adjacent ends of two other parallel shafts in mesh with said fixed gear, said other parallel shafts having sleeves fixed on their opposite ends provided with gears in mesh with a worm on said driving shaft, clutch members on each of said last mentioned parallel shafts between said sleeves and pinions and rotatable with said sleeves, a rocking beam for alternately moving said clutch members into and out of engagement with said pinions, a trip arm on said rocking beam, a tripping plate having a slot therein for engagement with said trip arm, and means associated with said tripping plate for moving the same in the arc of a circle in opposite directions, substantially as set forth.

8. A reversing gearing comprising a driving shaft, a plurality of parallel shafts at

an angle thereto, one of said parallel shafts being adapted to rotate a device alternately in opposite directions and having a gear fixed thereon, pinions loosely mounted on the adjacent ends of two other parallel shafts in mesh with said fixed gear, said other parallel shafts having sleeves fixed on their opposite ends provided with gears in mesh with a worm on said driving shaft, clutch members on each of said last mentioned parallel shafts between said sleeves and pinions and rotatable with said sleeves, a rocking beam for alternately moving said clutch members into and out of engagement with said pinions, a trip arm on said rocking beam, a tripping plate having a slot therein for engagement with said trip arm, means associated with said tripping plate for moving the same in the arc of a circle in opposite directions, and a spring projected rod for completing the movement of the tripping plate when shifted from one position to another, substantially as set forth.

In witness whereof, I have hereunto set my hand and seal at Indianapolis, Indiana, this 5th day of January, A. D. nineteen hundred and twenty-two.

HERBERT A. DAUM.
